DESIGN FOR A PEDESTAL FOR A TUMBLING BARREL

Lee B. Green, Lakewood, Ohio, assignor to The
Globe Machine & Stamping Company, Cleve-
land, Ohio, a corporation of Ohio

Application February 19, 1934, Serial No. 50,772

Term of patent 14 years

To all whom it may concern:

Be it known that I, LEE B. GREEN, a citizen of the United States, residing at Lakewood, in the county of Cuyahoga and State of Ohio, have invented a new, original, and ornamental Design for a Pedestal for a Tumbling Barrel, of which the following is a specification, reference being had to the accompanying drawing, forming part thereof.

In the drawing, Fig. 1 is a front elevation of a pedestal for a tumbling barrel, showing my new design.

Fig. 2 is a rear perspective view of the same.

I claim:

The ornamental design for a pedestal for a tumbling barrel, substantially as shown.
